UNITED STATES PATENT OFFICE.

JACOB G. PECK, OF PORTLAND, OREGON.

ICE-CREAM-HARDENING ROOM.

Application filed November 7, 1924. Serial No. 748,453.

To all whom it may concern:

Be it known that I, JACOB G. PECK, a citizen of the United States, residing at Portland, in the county of Multnomah and 5 State of Oregon, have invented certain new and useful Improvements in Ice-Cream-Hardening Rooms, of which the following is a specification.

My invention relates to the art of refrigeration and it especially has for its object to provide a refrigerating room for use in ice cream plants into which the cans or other containers of ice cream may be placed for the purpose of bringing their temperature 15 down low enough to harden the contents.

Among the objects of the invention are also to provide a hardening room which, while employing expansion coils, is of such arrangement and construction as to give 20 complete control to the defrosting of the coils and in such manner as not materially to raise the room temperature while the defrosting operation takes place; to provide defrosting means which will not require removal of the ice cream cans or containers 25 from the room during the time the defrosting takes place; to provide for positive air circulation purified by calcium and by circulating all around the ice cream containers, 30 thus ensuing quick hardening and uniform temperature; to provide means whereby the ice cream containers can be handled more rapidly and more efficiently, enabling them to be assorted and delivered with the least 35 possible expense of handling; to provide a structure with direct expansion cooling coils set in a pan within the room, which coils are used and operated under a flooded system employing the accumulator with or without 40 interior liquid cooling coils and connected either by means of a check valve or by the liquid as it rises in the accumulator, turning back through the suction line to the coils, coming in contact with the same liquid; 45 to eliminate suction and liquid headers, enabling the use of one expansion and one suction valve only; to provide for defrosting the coils by the use of cold brine taken from a pan located above the storage racks and 50 beneath the cooling coils, the brine being taken from the pan and discharged over the coils, means being provided to prevent splashing the brine down into that portion of the room below in which the ice cream 55 containers are located, the defrosting being

conducted without causing a rise in the temperature of the room.

Other objects of the invention will become apparent to those skilled in the art as the construction and operation of the invention is developed hereinafter.

Generically the invention comprises a unit consisting of a room having insulated floor, walls and roof or ceiling, within which is disposed a set of skeleton racks for 65 the ice cream containers and above which racks is located a brine pan that contains the defrosting liquid in which and above which the refrigerating coils are located, means being provided to pump the brine from the 70 pan over the tops of the coils for defrosting purposes, and other means being provided to prevent the brine splashing over and getting down onto the racks and their contents.

More subordinately invention also resides 75 in those novel structures, combinations and arrangements of parts, which will be hereinafter fully described, and then be specifically pointed out in the appended claims, reference being had to the accompanying 80 drawings, in which:

Figure 1 is a perspective view (parts being broken away) of a preferred embodiment of my invention.

Figure 2 is a central vertical longitudinal section of the same.

Figure 3 is a horizontal section on the line 3-3 of Figure 2.

Figure 4 is a cross section on the line 4-4 of Figure 2.

Figure 5 is an elevation of a modification.

Figure 6 is a plan view of said modification.

In the drawings, in which like numerals of reference designate like parts in all the figures, 26 designates the floor, 27 the walls and 28 the roof of the room in which is located the racks 24 for the containers 25 and the cooling and defrosting apparatus.

Within the room is located a brine tank 1 100 supported on transverse I-beams 36 and together with the non-insulated baffle floor 31, constituting a sub-ceiling for the storage space of the room. 2 designates the defrosting pipes which extend from the defrosting header 3 over the expansion coils 7, the latter being located in tiers with their lower sections emersed in brine within the pan or tank 1.

4 is the brine pipe which leads from the 110

- brine circulating pump 5 to the header 3, the pump 5 receiving the brine through a suction line 6, the entrant end of which is immersed in the brine in the tank or pan 1. 8 indicates the suction line from the expansion coils 7 in which line there is located the suction valve 9. 10 is the accumulator and 11 the suction line from the accumulator to the compressor (not shown).
- 12 is the liquor line in which is contained the expansion valve 13 and through which the refrigerating liquor is conducted to the expansion coils. 14 is a fan housing which communicates with the interior of the coil compartment through the opening in the front partition wall 20, the latter having the operator's door 29 and the entrance door 30 for obvious purposes. 15 is the fan which draws the air from the coil compartment and delivers it into a discharge duct 16 having openings 17 for passing the air down into the storage compartment of the room at one side.
- 18 is the return duct having openings 19 for receiving the air from the storage compartment of the room and discharging it to the rear of the coil compartment and preferably at a place diagonal to the entrance to the fan housing 14 so that the flow of air caused by the fan circulation will be as indicated by the arrows in Figure 1.
- Side baffle walls 21 are provided and these walls extend the full length of the pan or tank 1 and their bottoms are immersed within the liquid within the pan 1. These baffles 21 extend to the top or ceiling of the room and one of them extends clear to the back wall as shown in the left in Figure 1, while the other terminates short of the back wall to permit air discharge from the duct 18, but it has a lateral extension 21^x to the side wall, thereby providing a dead air space 21^y above the duct 18 which aids in heat insulation. A dead air space is also provided between the baffle 21, in the left in Figure 1, and the adjacent wall as indicated by 21^z for the same purpose, or if desired the baffles 21 may terminate short of the back wall so that the space 21^y will communicate at the back with the coil chamber proper.
- 22 designates the pump motor and 23 the fan motor while the ice cream containers are indicated by 25 and their storage shelving by 24.
- 55 In Figures 5 and 6 is shown a slight modification of the invention in which baffles 37 extend across the coil chamber and alternately extend from the bottom toward the top and from the top toward the bottom to provide a zigzag passage for the circulating air over the coil surfaces from the place of entrance to the place of exit.
- It will be noticed from the foregoing description, taken in connection with the accompanying drawings, that my invention

comprises a complete unit consisting of a refrigerating room in which is located the direct expansion coils set into a metallic tank which is supported by angle iron framing and in which is included the removable shelving to hold the ice cream containers. The tank 1 and coils 7 do not constitute a bunker system. By being set directly in the refrigerating room and by the pan containing the brine for defrosting it will act as a container of cold, giving practically uniform temperature at all times. Furthermore the provision of the front baffle wall 20 and the side partitions 21 that extend down into the brine within the tank 1 and run from there up to the ceiling of the room, any brine is prevented from splashing over during the defrosting operation, and by locating the place of air intake and air outlet as shown the air is caused to travel the full length and across the direct expansion coils and this air is also defrosted by means of the brine defrosting pump pumping the brine through the slotted pipes 2 over the coils (controlled by gate valves from a common header 3) thus giving a full circulation of the air without resistance.

It is to be noted that the pump is placed directly outside the room where it is easy to get at and the brine control valves and fan are all located in positions easily accessible.

It will also be noted that in my construction the calcium brine pan or tank is located directly over the ice cream container racks and as this tank has from six to ten inches of calcium chloride brine in the same, which is kept very cold by part of the coils being submerged in the brine, the brine in the pan is at all times below the temperature of the room and therefore it acts as a hold-over refrigerating medium for the room when the refrigerant circulation is cut off from the pipe 7 as during the defrosting interval. It is also important to note that in my arrangement the defrosting operation takes place through the use of cold brine, and brine which is always located within the room and is never at a temperature above that of the room, hence the defrosting operation can be conducted more freely (i. e., at shorter intervals) than under the usual practice with a result of a more efficient operation of the system because of the clean condition of the expansion coil pipes.

In practice I find that the defrosting operation, if conducted approximately once a week, is sufficient though it may be conducted at shorter intervals or longer intervals as conditions may warrant.

The brine during the defrosting operation delivering over the direct expansion coils, keeps them entirely free from frost, thereby giving the highest possible efficiency of radiating surface and giving free and un-

obstructed passage-way of the air circulation.

It is also to be noted that as the brine tank 1 is of metal and contains the cold brine the underside of that tank being exposed to the storage space of the room also acts as a cooling agent, thus adding to the efficiency of the system.

Again the air circulating over the brine 10 in the tank 1 is purified by the brine and chilled in passing the expansion coils and brine tank, enabling the temperature of the room to be easily carried at a uniform rate of from zero to ten below zero F., which by 15 experimentation has been found to be the best temperature for the freezing of ice cream.

With the use of my invention employing the removable iron shelves and supports the 20 ice cream cans and brick molds can be handled more rapidly and efficiently, more readily assorted and delivered to the trade with the least possible expense of handling; all available space is utilized to the best advantage 25 and more ice cream per unit of room can be installed than has heretofore been possible by the use of those rooms now generally employed.

From the foregoing description, taken in 30 connection with the accompanying drawings, it is thought the complete construction, and advantages of the invention will be clear to those skilled in the art.

What I claim is:

1. In ice cream hardening rooms, a room having an insulated floor, walls and ceiling, supports extending horizontally in said room, a brine pan held on said supports, a horizontal baffle extending around the pan 40 to the walls of the room, said baffle having air ports at the sides of the room, vertical baffles at the sides of the pan, the bottoms of which baffles project into the pan, expansion coils mounted over the pan in tiers, the 45 lower tiers lying within the pan, an inlet air duct located at one side of the pan to receive the air from the chamber beneath and deliver it to the rear of the coils, an outlet air duct located at the other side of the pan to deliver air to the chamber beneath, a fan for drawing the air from the room beneath through the inlet air duct and passing it over and between the expansion pipe coils and delivering it to the outlet air 55 duct for delivery back into the lower chamber, substantially as shown and described.

2. In ice cream hardening rooms, a room having an insulated floor, walls and ceiling, supports extending horizontally in said room, a brine pan held on said supports, a horizontal baffle extending around the pan 60 to the walls of the room, said baffle having air ports at the sides of the room, vertical baffles at the sides of the pan, the bottoms of which baffles project into the pan, expansion

coils mounted over the pan in tiers, the lower tiers lying within the pan, an inlet air duct located at one side of the pan to receive the air from the chamber beneath and deliver it to the rear of the coils, an 70 outlet air duct located at the other side of the pan to deliver air to the chamber beneath, a fan for drawing the air from the room beneath through the inlet air duct, and passing it over and between the expansion pipe coils and delivering it to the outlet air duct for delivery back into the lower chamber, defrosting pipes located above the expansion coils, and means for pumping brine from the tank to the said pipes for 80 delivery over the coils.

3. In refrigerating rooms, a brine pan separating the room into an upper and lower chamber, a transverse vertical baffle across said upper chamber, a horizontal baffle floor 85 between the front wall of said room and said transverse vertical baffle, skeleton racks in the lower chamber for holding the ice cream containers, expansion coils in said upper chamber, the lower ones of which are immersed in the brine tank, defrosting ducts located above the coils to discharge their contents over the coils, a pump for drawing brine from the tank and delivering it to the defrosting ducts, means for circulating air 90 through the room from the lower chamber into the upper chamber over and among the coils and back again to the lower chamber, and means restraining the defrosting brine 95 against splashing over into the lower chamber.

4. In refrigerating rooms, a brine pan separating the room into an upper and lower chamber, a transverse vertical baffle across said upper chamber, a horizontal baffle floor 105 between the front wall of said room and said transverse vertical baffle, skeleton racks in the lower chamber for holding the ice cream containers, expansion coils in said upper chamber, the lower ones of which are immersed in the brine tank, defrosting ducts located above the coils to discharge their contents over the coils, a pump for drawing brine from the tank and delivering it to the defrosting ducts, means for circulating air 110 through the room from the lower chamber into the upper chamber over and among the coils and back again to the lower chamber, means restraining the defrosting brine 115 against splashing over into the lower chamber, said restraining means comprising longitudinal vertical baffles at the sides of the tank and extending from the transverse vertical baffle toward the opposite wall of the room.

5. In refrigerating rooms, a brine pan separating the room into an upper and lower chamber, a transverse vertical baffle across said upper chamber, a horizontal baffle floor 120 between the front wall of said room and

and said transverse vertical baffle, skeleton racks in the lower chamber for holding the ice cream containers, expansion coils in said upper chamber, the lower ones of which are immersed in the brine tank, defrosting ducts located above the coils to discharge their contents over the coils, a pump for drawing brine from the tank and delivering it to the defrosting ducts, means for circulating air 10 through the room from the lower chamber into the upper chamber over and among the coils and back again to the lower chamber, means restraining the defrosting brine against splashing over into the lower chamber, said restraining means comprising longitudinal vertical baffles at the sides of the tank and extending from the transverse vertical baffle toward the opposite wall of the room, said circulating means comprising air ducts at each side of the upper chamber with ports communicating with the lower chamber, one of said ducts delivering the air from the lower chamber into the upper chamber at one corner, a fan for drawing 20 the air from said corner through and over the coils toward the diagonally opposite coils and delivering it to the other duct for passage back into the lower chamber, substantially as shown and described.

30 6. A refrigerating room composed of insulated floor, walls and ceiling with a similar insulated vestibule in communication with the lower part of said room, a horizontal partition baffle dividing said room into an upper and lower chamber and having a brine pan opening, skeleton shelving within the lower chamber to receive the containers of material to be chilled, a brine pan held in said opening and above said 35 shelving, vertical transverse and longitudinal baffle walls in the upper chamber at the front and side of said pan, refrigerating coils in said upper chamber and located over said pan, portions of certain of said 40 coils extending into the pan to chill the contents thereof, means to circulate a refrigerant through said coils, and means for drawing air from said lower chamber at one side into said upper chamber and delivering it 45 to the coils at one corner, causing it to pass over and around the coils to the diagonally opposite corner and then delivering the air back into the lower chamber at the side opposite to which it left the lower chamber, 50 substantially as specified.

55

7. A refrigerating room composed of insulated floor, walls and ceiling with a similar insulated vestibule in communication with the lower part of said room, a horizontal partition baffle dividing said room into an upper and lower chamber and having a brine pan opening, skeleton shelving within the lower chamber to receive the containers of material to be chilled, a brine pan held in said opening and above said

shelving, vertical transverse and longitudinal baffle walls in the upper chamber at the front and side of said pan, the side baffles extending from within the pan to the chilling of the room and the front baffle extending across the width of the room from the horizontal partition to the ceiling of the room, refrigerating coils in said upper chamber and located over said pan, portions of certain of said coils extending into the pan to chill the contents thereof, means to circulate a refrigerant through said coils, and means for drawing air from said lower chamber at one side into said upper chamber and delivering it to the coils at one corner causing it to pass over and-around the coils to the diagonally opposite corner and then delivering the air back into the lower chamber at the side opposite to which it left the lower chamber, substantially as shown and described. 70 75 80 85

8. A refrigerating room composed of insulated floor, walls and ceiling with a similar insulated vestibule in communication with the lower part of said room, a horizontal partition baffle dividing said room into an upper and lower chamber and having a brine pan opening, skeleton shelving within the lower chamber to receive the containers of material to be chilled, a brine pan held in said opening and above said shelving, vertical transverse and longitudinal baffle walls in the upper chamber at the front and side of said pan, refrigerating coils in said upper chamber and located over said pan, portions of certain of said coils extending into the pan to chill the contents thereof, means to circulate a refrigerant through said coils, and means for drawing air from said lower chamber at one side into said upper chamber and delivering it to the coils at one corner, causing it to pass over and around the coils to the diagonally opposite corner and then delivering the air back into the lower chamber at the side opposite to which it left the lower chamber, defrosting ducts located over the coils, and a pump to pump the brine from the tank to the defrosting ducts for defrosting purposes.

9. A refrigerating room composed of insulated floor, walls and ceiling with a similar insulated vestibule in communication with the lower part of said room, a horizontal partition baffle dividing said room into an upper and lower chamber and having a brine pan opening, skeleton shelving within the lower chamber to receive the containers of material to be chilled, a brine pan held in said opening and above said shelving, vertical transverse and longitudinal baffle walls in the upper chamber at the front and side of said pan, refrigerating coils in said upper chamber and located over said pan, portions of certain of said coils extending into the 120

pan to chill the contents thereof, means to circulate a refrigerant through said coils, and means for drawing air from said lower chamber at one side into said upper chamber and delivering it to the coils at one corner, causing it to pass over and around the coils to the diagonally opposite corner and then delivering the air back into the lower chamber at the side opposite to which it left 5 the lower chamber, defrosting ducts located over the coils, a pump to pump the brine from the tank to the defrosting ducts for defrosting purposes, said vertical transverse baffle partitions dividing said upper chamber into a front and back compartment, a header and control valves for said defrosting ducts located in the back compartment adjacent to said partition, said vertical transverse partition having a door to give 10 access to said valves, the front wall of the room also having a door to permit entry into said front compartment.

10. A refrigerating room composed of insulated floor, walls and ceiling with a similar insulated vestibule in communication with the lower part of said room, a horizontal partition baffle dividing said room into an upper and lower chamber and having a brine pan opening, skeleton shelving within 15 the lower chamber to receive the containers of material to be chilled, a brine pan held in said opening and above said shelving, vertical transverse and longitudinal baffle walls in the upper chamber at the front and side of said pan, refrigerating coils in said upper chamber and located over said pan, portions of certain of said coils extending into the pan to chill the contents thereof, means to circulate a refrigerant through said coils, and means for drawing air from said lower chamber at one side into 20 said upper chamber and delivering it to the coils at one corner, causing it to pass over and around the coils to the diagonally opposite corner and then delivering the air back into the lower chamber at the side opposite to which it left the lower chamber, defrosting ducts located over the coils, a pump to pump the brine from the tank to 25 the defrosting ducts for defrosting purposes, said vertical transverse baffle partitions dividing said upper chamber into a front and back compartment, a header and control valves for said defrosting ducts located in the back compartment adjacent to said partition, said vertical transverse partition having a door to give access to said valves, the front wall of the room also having a door to permit entry into said front compartment, 30 a vestibule at the front of the room with an entrance door from the outside, said room having a door communicating with the vestibule, said vestibule being of a height approximating that of the lower chamber, the roof of said vestibule constituting a support for the defrosting pump and a motor for operating the same.

11. A refrigerating room composed of insulated floor, walls and ceiling with a similar insulated vestibule in communication with the lower part of said room, a horizontal partition baffle dividing said room into an upper and lower chamber and having a brine pan opening, skeleton shelving within the lower chamber to receive the containers of material to be chilled, a brine pan held in said opening and above said shelving, vertical transverse and longitudinal baffle walls in the upper chamber at the front and side of said pan, refrigerating coils in said upper chamber and located over said pan, portions of certain of said coils extending into the pan to chill the contents thereof, means to circulate a refrigerant through said coils, and means for drawing air from said lower chamber at one side into said upper chamber and delivering it to the coils at one corner, causing it to pass over and around the coils to the diagonally opposite corner and then delivering the air back into the lower chamber at the side opposite to which it left the lower chamber, defrosting ducts located over the coils, a pump to pump the brine from the tank to the defrosting ducts for defrosting purposes, said vertical transverse baffle partitions dividing said upper chamber into a front and back compartment, a header and control valves for said defrosting ducts located in the back compartment adjacent to said partition, said vertical transverse partition having a door to give access to said valves, the front wall of the room also having a door to permit entry into said front compartment, a vestibule at the front of the room with an entrance door from the outside, said room having a door communicating with the vestibule, substantially as shown and described.

12. In refrigerating rooms, a brine pan separating the room into an upper and lower chamber, a transverse vertical baffle across said upper chamber, a horizontal baffle floor between the front wall of said room and said transverse vertical baffle, skeleton racks in the lower chamber for holding the ice cream containers, expansion coils in said upper chamber, defrosting ducts located above the coils to discharge their contents over the coils, a pump for drawing brine from the tank and delivering it to the defrosting ducts, means for circulating air through the room from the lower chamber into the upper chamber over and among the coils and back again to the lower chamber, and means restraining the defrosting brine against splashing over into the lower chamber.

11. A refrigerating room composed of in-

JACOB G. PECK.
